UNITED STATES PATENT OFFICE.

WALTER J. SCOTT, OF WOONSOCKET, RHODE ISLAND.

ELECTRIC STOP MOTION FOR DRAWING FRAMES.

Application filed March 9, 1928. Serial No. 260,323.

This invention relates to an electric stop motion for drawing frames; and has for its object to provide a stop motion of this character which is located intermediate the supply packages and the draft rolls where an electric contact member is arranged to be affected by the falling of a broken sliver end to affect the circuit and stop the machine.

A further object of the invention is the positioning of a guide member intermediate the supply packages and the draft rolls and to provide a flexible electric contact member in the electric circuit positioned to normally open the circuit, the contact member being arranged to move inwardly by the weight of a broken sliver end upon it to complete the circuit and energize a magnet to release the lever to shift the belt or otherwise stop the machine.

With these and other objects in view, the invention consists of certain novel features of construction, as will be more fully described, and particularly pointed out in the appended claims.

In the accompanying drawings:

Fig. 1 is a side elevation showing the general arrangement of the usual mechanism of a drawing frame with my improved stop motion applied thereto.

Fig. 2 is a side elevation of the guide for the plurality of slivers with my improved circuit closing finger mounted adjacent thereto.

Fig. 3 is a section on line 3—3 of Fig. 2.

Fig. 4 is a perspective view of the mechanism shown in Fig. 2.

Fig. 5 is a detail partly in section illustrating the solenoid magnet in position to move the latch and release the belt shift mechanism.

Fig. 6 is a view illustrating the belt shift lever as retained in operative position against the tension of the belt shifting spring, the lever being arranged to be released by a solenoid magnet when the electric circuit is closed.

Fig. 7 is a diagrammatic view illustrating the wiring diagram in which the contact finger is arranged to close the circuit for operating the belt shift lever.

It is found in the practical operation of drawing frames of this character, that where a plurality of supply packages are mounted and from each of which a sliver is led thru the guide to be acted on by a set of drawing rolls, often one or more of these slivers intermediate the supply packages and the guide or drawing rolls breaks, and when this occurs those slivers remaining continue to run and

form thin places in the yarn which may run for some time before being discovered by the operator; and to obviate this difficulty, I have mounted a stop motion intermediate the supply and the drawing rolls so that if any one or more of these in the set or group of slivers should break at a point intermediate the supply and the rolls the falling of the broken end will serve to stop the machine either by opening or by closing the electric circuit and so call the attention of the operator to the broken sliver before the damage is done, it being only necessary then to piece up these broken ends and start the machine again; and the following is a detailed description of the present embodiment of my invention and showing one means by which these advantageous results may be accomplished.

With reference to the drawings, 10 designates the supply packages which may be spools or bobbins on which the slivers 11 are wound and from which packages the slivers are led thru the slots 12 in the guide frame 13, thence over and around the back draft rolls 14 thru the carrier rolls 15 and the front draft rolls 16 and after being drawn out or drafted the yarn is fed thru the flyer 17 to be wound upon the spool or bobbin 18 which is raised and lowered thru action of the rack 19 and pinion 20 and rapidly rotated by the whirl 21 thru the belt 22 from the pulley 23.

It is found in practice that often the sliver ends break down at some point between the supply packages 10 and the guide frame 13 and when this occurs the remaining slivers continue without the end broken down, which forms a thin place in the yarn and if later discovered necessitates the cutting out and loss of the thin portion, piecing up of the broken ends and the starting over again with the required number of ends. Therefore, to obviate this annoying difficulty, I have mounted a stop motion contact member at a point intermediate the supply packages and guide plate which is herein shown as comprising a readily bendable finger 24 forming part of an electric circuit 25 and providing a contact member 26 formed of carbon and set into the guide arm 27, which guide arm is connected thru the bolt 28 to the bar 29.

This flexible bendable finger is supported in this bar 29 and insulated therefrom as at 30, and connected to the circuit thru the wire 31, the other wire of the circuit 32 being connected to the bar 29. This guide plate is set at an incline to the line of travel of the slivers

11 between the supply and the guide plate, as best illustrated in Fig. 1, whereby if any one of these slivers should break down the broken end would fall and rest upon this flexible 5 finger 24, whereby its weight would cause this finger to spring inwardly into contact with the carbon plug 26, thus completing the circuit to energize the electromagnet 33, trip the latch 34 and release the lever 35, which thru 10 the action of spring 39, throws the rod 36 and shifts the belt from the tight pulley 37 to the loose pulley 38, thus stopping the machine. By employing a carbon plug thru 15 which to make the circuit, sparking is obviated. The electric circuit is herein shown as being normally open but to so arrange the finger 24 that its movement will open the circuit instead of closing it, will fall within the spirit and scope of this invention.

20 My improved stop motion for drawing frames is extremely simple and practical in its construction and operation and by its use much time is saved and the waste of good textile material is prevented, as the moment a 25 sliver is broken notice is immediately given to the operator who pieces up the ends and after the trouble is corrected the machine is started again.

The foregoing description is directed solely 30 towards the construction illustrated, but I desire it to be understood that I reserve the privilege of resorting to all the mechanical changes to which the device is susceptible, the invention being defined and limited only by 35 the terms of the appended claims.

I claim:

1. In an electric stop motion for drawing frames, an electric circuit, a stop motion in said circuit, a set of sliver supply packages, 40 draft rolls and a single circuit closing member located intermediate the supply packages and the draft rolls arranged to be actuated by any one of a plurality of broken slivers to stop the machine if a sliver breaks between these 45 points.

2. In an electric stop motion for drawing

frames, an electric circuit, a stop motion in said circuit, a set of sliver supply packages, draft rolls for the sliver, a movable contact member located intermediate said supply and 50 rolls supported in inoperative position independent of the slivers and arranged to be actuated by the weight of a broken sliver end to affect the circuit and stop the machine.

3. In an electric stop motion for drawing frames, an electric circuit, a stop motion in said circuit, a plurality of sliver supply packages, a set of draft rolls for the sliver, a sliver guide located intermediate said packages and 55 said rolls, a flexible contact member in said circuit supported in inoperative position independent of said slivers and located adjacent said guide and arranged to be actuated by the weight of any one of a plurality of broken sliver ends to close the circuit and stop the 60 machine.

4. In an electric stop motion for drawing frames, an electric circuit, a stop motion in said circuit, a plurality of sliver supply packages, a set of draft rolls for the sliver, a sliver 65 guide set adjacent the back draft rolls and on an incline to the line of travel of the sliver from the packages, the same having a movable contact finger normally held out of operating position to open the circuit by means 70 independent of the slivers and arranged to be moved by the falling of a broken sliver end to close the circuit and stop the machine.

5. In an electric stop motion for drawing frames, an electric circuit, a stop motion in 75 said circuit, a set of sliver supply packages, front and back draft rolls, a sliver guide located adjacent said back draft rolls and on an incline to the line of travel of the slivers 80 from the supply packages, a flexible contact finger set to normally open the circuit and arranged to be forced into position to close the circuit by the weight of any one of the set of broken sliver ends and stop the machine.

In testimony whereof I affix my signature.

WALTER J. SCOTT.
